United States Patent

Des. 238,323

Patented Jan. 6, 1976

238,323

DIAPER HOLDER

Phyllis A. Jackson, 8410 Silver Star,
San Antonio, Tex. 78218

Filed Sept. 19, 1974, Ser. No. 507,529

Term of patent 14 years

Int. Cl. D6—04; D7—07

U.S. Cl. D6—131

FIG. 1

FIG. 2

FIG. 3

FIG. 1 is a front perspective view of a diaper holder, showing my new design.

FIG. 2 is a rear perspective view.

FIG. 3 is a side elevation view taken from the left of FIG. 1.

The broken lines in FIG. 1 and FIG. 2 represent conventional stitching.

I claim:

The ornamental design for a diaper holder, substantially as shown and described.
